Filed May 6, 1970, Ser. No. 22,842

Term of patent 14 years

Int. Cl. D23—02

U.S. Cl. D23—48

FIG. 3.

FIG. 4.

FIG. 5

FIG. 1 is a perspective view of the "portable commode" showing my new design as seen from a point above and to the right thereof with the lid open;

FIG. 2 is a perspective view from the same position as FIG. 1 with the lid closed;

FIG. 3 is a perspective view from the same position as FIGS. 1 and 2 but with the lid removed and the body shown in open position atop the base;

FIG. 4 is a top plan view with the top removed;

FIG. 5 is a fragmentary section to an enlarged scale taken along line 5-5 of FIG. 4.

The side surface of the article is the same in appearance throughout while the bottom is conventionally flat and unornamented.

I claim:

The ornamental design for the portable commode, as shown and described.
